UNITED STATES PATENT OFFICE.

HARRY RANDOLPH VAN DEVENTER, OF SUMTER, SOUTH CAROLINA, ASSIGNOR, BY MESNE ASSIGNMENTS, TO SPLITDORF ELECTRICAL COMPANY, OF NEWARK, NEW JERSEY, A CORPORATION OF NEW YORK.

IGNITION MECHANISM FOR INTERNAL-COMBUSTION ENGINES.

1,267,148.

Specification of Letters Patent.

Patented May 21, 1918.

Application filed December 18, 1914. Serial No. 878,196.

To all whom it may concern:

Be it known that I, HARRY RANDOLPH VAN DEVENTER, a citizen of the United States, residing at Sumter, in the county of 5 Sumter and State of South Carolina, have invented certain new and useful Improvements in Igniter Mechanism for Internal-Combustion Engines, of which the following is a specification, reference being had to the 10 accompanying drawings.

This invention relates to ignition apparatus for internal combustion engines and has for its purpose the provision of an igniter bracket upon which a magneto may be 15 mounted, the magneto armature or rotor being oscillated by means of suitable mechanism carried entirely upon the igniter bracket.

A further object is to provide a bracket 20 adapted to be mounted on an engine and carrying the engine igniter and the magneto and all of the operating means therefor, said means being so disposed in regard to the engine push rod or other actuating device 25 that the magneto may be removed without interfering in any way with the operation of the igniter proper. This permits a suitable source of current to be connected to the igniter in the event of any trouble with the 30 magneto as the operation of the igniter does not depend on any springs or other parts heretofore mounted upon and forming part of the magneto.

A device of the foregoing description is 35 shown in my pending application Serial No. 864,447. In said application I have shown and claimed a structure as just described, and while the foregoing arrangement has given excellent results, I have found it possible 40 to increase the efficiency of same by a more compact arrangement of the various parts, the elimination of a separate bearing support for the trip lever, and the arrangement of the magneto whereby the axis of the 45 armature shaft coincides with the axis of the shaft of the movable electrode in the igniter.

The foregoing points constitute the leading 50 features of improvement which will be described and claimed in this application, and ancillary features will sufficiently appear from the detailed description hereafter.

My invention is illustrated in the accompanying drawings in which—

Figure 1 is a view looking down on the top of an apparatus embodying my invention.

Fig. 2, a front view of the same with the magneto removed.

Fig. 3, a side view of Fig. 1.

Like figures of reference denote the same parts wherever they are shown.

1 denotes a section of the wall of the engine cylinder, to permit the igniter body 2 to be shown. This carries the movable contact 3 and the fixed contact 4 constituting the usual make and break igniter mechanism. A flange 5 projects around the aperture in the cylinder, and projecting from this flange and preferably integral therewith are the arms 6 and 7 supporting studs 8 and 9, carrying rollers 10 and 11, for the ends of springs 12 and 13. The remaining ends of said springs are carried on rollers suitably attached to the trip lever 14, which is loosely mounted on the shaft 15 of the movable electrode 3, it being understood that the shaft forms a support for the trip lever 14 but does not move therewith. Trip lever 14 is provided with an igniter firing finger 16, a bifurcated finger 17, and a trip finger 18, the latter adapted to be engaged by the push rod 19, the outer end of said rod being suitably connected to some moving part of the engine so that the rod has a reciprocating motion over the pulley 20 which causes the inner end 21 of the rod to push inwardly against 18 until same is suddenly released and rides under it. Such a trip motion is now commonly used in connection with make and break igniters.

The shaft 15 of the movable contact 3 of the igniter carries at its outer end an arm 22 having suitable adjusting means such as the screw 23 whereby the relative position of 22 and the firing finger 16 on the trip lever may be adjusted. This is occasioned by the necessity, when some magnetos are used, of having the igniter contacts closed, while again when battery is used it is preferable to have the igniter contacts normally open.

A spring 24 or any other suitable means

- may be employed to hold the contacts of the igniter together which is accomplished by securing one end of said spring to the flange 5 and the other end to the arm 22.
- 5 Projecting from the flange 5 and preferably integral therewith is a support 25 upon which may be mounted any suitable magneto 26. Upon the shaft of this magneto is a dog 27, a crank pin 28 on which is 10 positioned between the fingers 17 of a bifurcated trip lever 14. A connection 29 is made between the circuit terminal 30 of the magneto and the binding post 31 on the outer end of the fixed contact 4 of the igniter, 15 this fixed contact being suitably insulated from the igniter body 2 in the usual manner. The circuit is completed through the movable contacts 3 of the igniter, and framework of the igniter mechanism and magneto.
- 20 Any suitable type of magneto may be used. Presuming the magneto to be of the alternating current type, the armature or rotor of same is so set in relation to the dog 27 that when the dog is moved to the right, 25 facing Fig. 1, and suddenly released, the peak of the current wave produced by the movement of the armature will occur at the same time the igniter points, in the cylinder, separate. This is accomplished by the push 30 rod 19 engaging trip finger 18, thereby pushing trip lever 14 to the left until 18 trips under the end 21 of rod 19. When this occurs, spring 12 and 13 cause a quick return of the trip lever to its normal or central position, and fingers 17 engaging the lower end 28 of the dog 27 cause a correspondingly rapid movement of the dog, thereby actuating the magneto. At the proper time, in the cycle of operations the 35 40 firing finger 16 strikes the lower end of the screw 23, which moves arm 22 rigidly attached to shaft 15 thereby causing a spark at the separation of the igniter contacts in the cylinder.
- 45 To prevent the operation of the igniter mechanism during the idle strokes of the engine, the exhaust valve push rod 32 which has a reciprocating motion, is provided with suitable means such as the pin 33 adapted 50 to engage the arm 34 of a bell crank lever, the upper end 35 of which is positioned under push rod 19, so that when the exhaust rod is actuated, which occurs during the idle stroke of the piston on "hit-and-miss" engines, or when the exhaust valve is held open 55 by the governor, the bell crank lever will occupy the position shown in dotted lines, thereby lifting the push rod 19 above finger 18, which prevents the operation of the igniter mechanism, the rod 19 reciprocating idly above finger 18 without engaging same.
- I also provide a shaft 36 upon which pulley 20 is eccentrically mounted, moving the arm 37 to the right or left (facing Fig. 60 65 2), the end 21 of push rod 19 is raised or

lowered in its relation to finger 18, thereby varying the time of ignition.

If desired, the magneto may be removed by merely unbolting it from the support 25, and simultaneously removing the wire 29 70 from the binding post 31. Any other suitable source of current may then be connected to post 31 and the engine may be operated without the magneto, as the parts that operate the igniter, and which coact as between the same and the engine, are not disturbed.

Referring to my pending application hereinbefore mentioned, it will be evident upon comparison with the foregoing description that one of the principal features of improvement herein disclosed consists of the mounting of the trip lever 14 directly upon the shaft 15, thereby eliminating a separate bearing and support for the trip lever which are shown in said prior application. This improvement also permits mounting the magneto so that the axis of its shaft coincides with the axis of the igniter shaft 15, making a mechanically correct and compact arrangement.

Another important feature is the location of the spring arms in a plane passing through the axes of movement of both the rods 19 and 32. If placed in either a horizontal or vertical plane, they would interfere with the compact arrangement of the various other parts.

While I have shown and described herein a preferred specific embodiment of my invention, it should be understood that there are many modifications which will suggest themselves to those skilled in the art, and I deem all such changes to be within the scope of my invention.

Having thus described my invention, what I claim and desire to secure by Letters Patent is:—

1. An ignition mechanism for internal combustion engines including in combination, an igniter having a movable electrode, a magneto having a rotor shaft in alinement with the axis of the movable electrode, an arm fixed to said shaft, an operating mechanism for the rotor, said mechanism comprising an arm mounted to turn about the axis of the movable electrode, means for operating said arm, and means for detachably connecting said arm to the arm on the rotor shaft.

2. An ignition mechanism for internal combustion engines, including in combination, a supporting bracket, an igniter having a movable electrode, a magneto detachably connected to said bracket and having its rotor shaft in alinement with the axis of the movable electrode, means mounted on the shaft supporting the movable electrode for operating the rotor of the magneto, said operating means being detachably connect-

ed with the rotor shaft whereby the magneto may be removed from the supporting bracket as a unit.

3. The combination of a magneto, and operating mechanism therefor, said magneto comprising a rotor shaft, and an arm fixed to said shaft, said mechanism comprising a shaft co-axial with said magneto shaft, an arm mounted on said mechanism shaft, said 10 arm having a slot therein, said magneto arm passing into said slot, and means for operating said mechanism arm.

4. The combination of a magneto, a supporting bracket on which said magneto is 15 removably supported, and an operating mechanism for the magneto shaft supported independently of the magneto and including a rotatable member having its axis in alinement with the axis of the magneto 20 shaft, a finger projecting from said member, an arm fixed to the member, resilient means connected to said member and supported independently of the magneto, a push rod for operatively engaging said finger, and means 25 for detachably connecting the arm on said rotatable member with the rotor shaft.

5. The combination of a magneto having a rotor shaft, an arm fixed to said rotor shaft, an igniter including a movable electrode 30 having its axis in alinement with the axis of the magneto shaft, a rotatable member mounted on the supporting shaft of the movable electrode, a finger projecting from 35 said member, a push rod adapted to engage said finger for oscillating said rotatable member, resilient means connected with said member and supported independently of the magneto, an arm fixed to said member, and means for detachably connecting 40 said arm to the arm on the rotor shaft.

6. In combination with an internal combustion engine, a framework secured to the engine cylinder, a shaft bearing in the framework, a pair of electrodes within the 45 cylinder one of which is mounted on said shaft, a magneto removably supported by

the framework having the rotor thereof detachably connected with said shaft, means connected with the shaft arranged to be engaged by an engine driven member to oscillate the shaft and rotor together with springs positively connected with said shaft arranged to quickly return the shaft and parts connected therewith to normal to effect the operation of the electrodes and generate a current in the magneto when the shaft is oscillated by the engine driven member and released.

7. The combination of a magneto, a supporting bracket on which said magneto is 60 removably supported, and an operating mechanism for the magneto shaft supported independently of the magneto and including a rotatable member having its axis in alinement with the axis of the magneto 65 shaft, a finger projecting from said member, an arm fixed to the member, resilient means connected to said member and supported independently of the magneto, and means for detachably connecting the arm 70 on said rotatable member with the rotor shaft.

8. The combination of a magneto having a rotor shaft, an arm fixed to said rotor shaft, an igniter including a movable electrode 75 having its axis in alinement with the axis of the magneto shaft, a rotatable member mounted on the supporting shaft of the movable electrode, a finger projecting from 80 said member, resilient means connected with said member and supported independently of the magneto, an arm fixed to said member, and means for detachably connecting said arm to the arm on the rotor shaft.

In testimony whereof I hereunto affix my signature in the presence of two witnesses.

HARRY RANDOLPH VAN DEVENTER.
